UNITED STATES PATENT OFFICE.

PETER L. HOFFMAN, OF AURORA, ILLINOIS, ASSIGNOR TO RICHARDS-WILCOX
MANUFACTURING COMPANY, OF AURORA, ILLINOIS, A CORPORATION OF
ILLINOIS.

DOOR-HANGER.

1,150,192.

Specification of Letters Patent. Patented Aug. 17, 1915.

Application filed May 9, 1913. Serial No. 766,586.

To all whom it may concern:

Be it known that I, PETER L. HOFFMAN, citizen of the United States, residing at Aurora, in the county of Kane and State of Illinois, have invented certain new and useful Improvements in Door-Hangers, of which the following is a specification.

This invention relates to improvements in the class of hangers for sliding doors commonly known as flexible hangers, in that they comprise a flexible or hinging connection between the frame of the hanger or the portion that rides on the supporting track, and the apron or straps which are secured to the door and serve as the direct suspension means for the latter.

One of the objects of the improvements embodied in this application, is to provide a hanger especially adapted for use with a tubular track, of simple and strong construction, being made of but few pieces, and in which provision is made against the derailment or jumping of the frame from the track.

A further object is to provide a hanger of the class described, in which the door suspended therefrom may swing freely outwardly or away from the structure for which the door is provided, without affecting the vertical alinement of the hanger frame and the position of the wheel on the track, and will maintain the hanger-frame and door in true vertical alinement should the door swing laterally toward the building.

A further object of my invention is to provide an adjustable connection between the hanger frame and the door straps or apron so that the latter may be fitted to doors of varying thickness and the center of the door maintained in the central vertical plane of the track and trolley wheel.

Other objects of general utility are served by my invention as will be apparent to those skilled in the art to which it relates.

In the accompanying drawing indicating a preferred form of my invention:—Figure 1 is a side view of my improved hanger shown in normal operative relation with a section of tubular track upon which it is slidably mounted; Fig. 2 is a side elevation of the parts shown in Fig. 1, but showing the pendant portion of the hanger in the position it will assume when the door is swung

laterally outwardly on the pivot bolt which connects said pendant and the hanger frame; Fig. 3 is a front elevational view of the parts shown in Figs. 1 and 2, taken at the inner side of the hanger.

60

Referring to the details of the drawing, the reference numeral 4 indicates the hood portion of a cast iron hanger frame from which extends downwardly a neck 4^a, which connects the hood 4 with an extension comprising two lugs each having an upwardly curved toe portion 4^b, and heel portions 4^c, the latter having flat under-surfaces 4^d, said lugs or foot extensions being spaced apart as shown in Fig. 3, and having extending 70 horizontally therethrough openings to receive a pivot bolt 8.

65

Mounted to swing on the portions of the bolt 8 projecting from the outer sides of the lugs 4^c, is a stirrup 7 made of a single 75 piece of strap metal bent outwardly from its pivotal point, as at 7^a, and again bent to provide the horizontal portion 7^b, which is centrally perforated to receive a bolt 11 which connects the right-angled apron 80 plates 9 and 10 with said stirrup. The upper horizontal portions of the apron plates are slotted to receive the bolt 11 whereby said apron members may be adjusted relative to each other on said bolt 85 and thus adapt them to doors of different thickness placed between and bolted to said members in the usual manner. The slots referred to are not shown in detail because they are well known features in hangers. 90

12 represents a tubular track formed with a longitudinal slot along one side adapted to receive any suitable supporting bracket (not shown), by which it is connected with a building. A wheel 5 is mounted on a 95 spindle or axle 6, which has suitable bearings in the opposite walls of the frame hood 4, the periphery or tread of the wheel concentrically conforming to the tubular track 12. The inner wall of the vertical portion 100 4^a of the hanger frame, is formed with a curved surface 4^e which is concentric with the walls of the tubular track 12, and extends out to the toe 4^b. The distance between this curved surface 4^e and the toe 4^b, 105 and the tread of the wheel 5 is such that the hanger cannot be removed from the track by lateral movement, but must be placed upon and disconnected from the track at the ends of the latter.

110

When the hanger described is in its normal position, the flat under-surfaces 4^a of the feet 4^c, rest against the upper surface of the apron strap 9, and thus maintain the several members 4, 7, 9, and 10, of the hanger, in true vertical alinement with the central vertical plane of the track even though the door embraced by the straps 9—10 should be pushed laterally inwardly, thereby effecting a rigid relation which is highly desirable. If, however, it should be desirable to swing the door laterally in an outward direction or away from the structure for which it is provided, such movement can take place freely without disturbing the vertical position on its track of the hanger frame, such arrangement being clearly indicated in Fig. 2.

It will be obvious that the curved inner wall 4^e while permitting the free longitudinal sliding of the hanger frame on the track serves as a guide for the hanger, and will also form an effective stop to prevent derailment of the hanger should the latter be pushed upwardly as an incident of the operation of the door suspended from the hanger.

Constructed as described, it will be seen that the hanger frame proper, including the bearings for the spindle or axle 6, and in-

cluding the extensions 4^b, 4^c, and the bearings for the pivot bolt 8, is a single casting.

The pendant portions of my improved hanger, including the stirrups 7 and the apron straps 9—10, are included in other co-pending applications for patents, and I therefore do not claim same *per se*, but

What I claim and desire to secure by Letters Patent, is:—

A door hanger comprising a combination with apron plates for attachment to a door, and a stirrup adjustably secured to said plates, a casting providing a wheel housing within which is journaled a wheel, the lower portion of which casting terminates in an integral lug to which said stirrup is pendently secured, a lateral integral projection from said lug against which the apron plates impinge when the door is in a vertical plane, and a lateral integral projection above said lug, against which the track upon which said wheel travels is adapted to abut when said hanger is thrown out of its vertical plane.

In testimony whereof I affix my signature in the presence of two witnesses.

PETER L. HOFFMAN.
